(57) **CLAIM**

I claim the ornamental design for a grommet-outfitted automotive air induction system mounting bracket, as shown and described.

DESCRIPTION

FIG. 1 of the drawings is a perspective view showing the front, top, and right side of a grommet-outfitted automotive air induction system mounting bracket embodying the design of my invention;

FIG. 2 is a left side elevation view;

FIG. 3 is a back elevation view;

FIG. 4 is a bottom plan view; and,

FIG. 5 is a perspective view of the mounting bracket in FIG. 1 shown in a condition of use.

The broken lines in FIG. 5 are for illustrative purposes only and form no part of the claimed design.
